DESIGN FOR A FOUNTAIN PEN OR SIMILAR ARTICLE

Harry E. Smith, Short Hills, N. J., assignor to
Celluloid Corporation, a corporation of New
Jersey

Application February 7, 1936, Serial No. 61,023

Term of patent 7 years

To all whom it may concern:

Be it known that I, Harry E. Smith, a citizen of the United States, residing at Short Hills, county of Essex, State of New Jersey, have invented a new, original, and ornamental Design for a Fountain Pen or Similar Article, of which the following is a specification, reference being had to the accompanying drawing, forming part thereof.

In the accompanying drawing:

The figure is a plan view of a fountain pen showing my new design.

The ornamentation of the fountain pen shown in the drawing comprises vertical strips, each strip being composed of alternating strata of contrasting colors. The strata in the adjacent vertical strips are arranged at sharply different angles.

I claim:

The ornamental design for a fountain pen or similar article substantially as shown and described.

HARRY E. SMITH.
